TOILET DEODORIZING DEVICE

Thomas Christian, 602 W. Hively St., and Jack L. Youngblood, 401 Hively St., both of Elkhart, Ind. 46514
Filed Mar. 2, 1966, Ser. No. 531,125
5 Claims. (Cl. 4—213)

This invention relates to improvements in toilet deodorizing devices, and more particularly to devices of the character disclosed in the co-pending patent application of Jack L. Youngblood, Ser. No. 499,363, filed Oct. 21, 1965.

The primary object of this invention is to provide a device of this character which is simple and inexpensive in construction, is compact and readily assembled and mounted, has minimum exposed parts which are attractive in appearance as exposed, and which is sanitary and readily cleaned.

A further object is to provide a deodorizing device which is readily, easily and quickly mounted upon or attached to an existing toilet seat assembly.

A further object is to provide a device of this character wherein the entire toilet deodorizing device is self-contained or of unitary construction, including its air intake portion, its blower and its filter.

A further object is to provide a device of this character which is unitary or self-contained and which is adapted to be activated by storage batteries or a storage battery.

A further object is to provide a device of this character having novel means for collecting air from a toilet device for delivery to air filtering and purifying means.

Referring to the drawings which illustrate the preferred embodiments of the invention,

FIG. 1 is a perspective view illustrating one embodiment of the invention as applied to a toilet device;

FIG. 2 is a perspective view of the air intake portion of the embodiment of the invention illustrated in FIG. 1;

FIG. 3 is a fragmentary detail sectional view taken on line 3—3 of FIG. 2;

FIG. 4 is a top plan view illustrating another embodiment of the invention as applied to a toilet device;

FIG. 5 is a fragmentary side elevational view of the device as seen in the direction of the arrow appearing in FIG. 4;

FIG. 6 is a fragmentary vertical sectional view taken on line 6—6 of FIG. 4;

FIG. 7 is a top plan view of another embodiment of the invention as applied to a toilet device;

FIG. 8 is a fragmentary vertical sectional view taken on line 8—8 of FIG. 7;

FIG. 9 is a fragmentary vertical sectional view similar to FIG. 8 but illustrating a modification of the invention;

FIG. 10 is a sectional detail view taken on line 10—10 of FIG. 8;

FIG. 11 is a sectional view similar to FIG. 10 and illustrating a slight variation in the construction;

FIG. 12 is a sectional view similar to FIG. 10 but illustrating another variation of construction;

FIG. 13 is a sectional view similar to FIG. 10 but illustrating still another variation of the invention.

Referring to FIGS. 1, 2 and 3 of the drawing which illustrate one embodiment of the invention, the numeral 10 designates a toilet bowl upon which is pivotally mounted a toilet seat 12 and a seat lid 14. A water tank

2

16 is operatively associated with the toilet bowl in the manner well understood in the art, being normally positioned rearwardly and above the rear portion of the toilet bowl. The usual connections of the tank and the bowl will be provided to accommodate functioning of the parts in a manner well understood in the art. The pivotal mounting or connection of the seat 12 and seat lid 14 with the toilet bowl is provided by conventional hinge means 18.

My toilet deodorizing device includes an air inlet or collection unit 20 which is adapted to be mounted upon the toilet seat 12 at the bottom thereof in the space which normally is provided between the seat 12 and the top of the bowl 10. This collection means is preferably substantially arcuate in shape to follow the curved shape of the rear portion of the seat and is shallow. Member 20 preferably constitutes a flat upper wall 22 and a flat lower wall 24, both arcuate and similar, which register with one another and are interconnected by an outer wall 26 and end walls 28. An elongated slot 30 is formed at the inner edges of the upper and lower walls 22 and 24. Registering apertures 32 in the upper and lower walls 22 and 24 accommodate securing screws 34. A flat tubular projection 36 extends rearwardly in substantially the plane of the member 20 from one end thereof and terminates in a cylindrical tubular end portion 38 which preferably is substantially axially aligned with the hinge 18.

A blower and filter unit 40 of any suitable construction is adapted to be detachably mounted upon a support, such as a wall, preferably below the water tank 16. The blower and filter unit preferably includes a housing having an opening 42 in one end wall thereof spanned by a reticulated member 44 forming the outlet of the housing. A filter unit (not shown) preferably formed of activated charcoal is mounted at the housing opening 42 and a blower (not shown) is mounted in the casing to a direct air to the filter unit and an intake provided by the fitting 46. Any suitable coupling 48 or connection means accommodates connection of the tube end 38 with the intake fitting 46, the same having relatively rotatable parts accommodating pivotal movement of the lid 14 and toilet seat 12. It will be understood that in the event that the cylindrical tube end part 38 is not axially aligned with the hinge 18, or in the event the position of the mounting of the blower and filter unit 40 does not accommodate a fitting 46 having a part axially aligned with the cylindrical tube end part 38, connection of the parts 38 and 46 may be effected through a flexible hose 50 and couplings at the ends thereof at 52 connected respectively with the parts 38 and 46.

By reason of the configuration of the air intake member 20 it is readily and simply mounted upon a conventional toilet seat rapidly and without the use of special tools. Thus it is possible for a householder to install a deodorizing unit by the use of a simple kit consisting of the member 20, the blower and filter unit 40 and either coupling 48 or flexible hose 50 and couplings 52. The member 20 is normally concealed so that only a part of the unit, as illustrated in FIG. 1 is visible, and this can be of inconspicuous character or can be constructed to be attractive in appearance. The air intake member 20, by reason of the length of the inlet slot 30 thereof, can effectively collect odor bearing air from the toilet seat to be conveyed to and through the blower and filter unit

for discharge after deodorizing thereof by the activated charcoal filter or any other suitable filter utilized therein.

A modified embodiment of the invention may require the use of a toilet seat 12' of special configuration as illustrated in FIGS. 4, 5 and 6. Curved or arcuate ribs 56 extend around rear portions of the seat 12', from bowl-engaging supports 54, having slight clearance with the top of the bowl 10 and spaced apart at 58 to receive therebetween an air intake or collection member having a shallow tube portion 60 communicating with a rear transverse hinging tube 62 journaled by brackets 64 secured to the bowl 10 by securing members 66. The lid 14 is journaled upon the tube 66 by brackets 68. One end of the tube 62 may be closed. The other tube end 70 projects laterally of the seat and is adapted for a sealed rotatable fit within a fitting member 72 carried by an air inlet conduit 74 connected to the blower and filter unit 40. It will be understood that ribs 56 need not be integral with the seat, but may be separate parts secured to the seat.

The embodiment of the invention illustrated in FIGS. 4, 5 and 6 provides a simple, economical and attractive deodorizing unit with minimum exposed parts, and requires only the special seat 12', or separate attached ribs 56, and the tubular collection and hinge parts 60, 62, 64 and 68 in addition to the blower and filter unit 40, the air inlet conduit 74 and the fitting 72. Thus by preforming the parts to be attached and providing them with convenient mounting means, any toilet may be converted quickly to use the deodorizing means.

It may be desirable in some instances to provide a unitary or self-contained deodorizing unit which does not require separate mounting of the blower and filter unit. In such an instance, a construction of the type illustrated in FIGS. 7 to 13, inclusive, may be utilized.

Referring to FIGS. 7 to 10, inclusive, an elongated tubular member 76 of cylindrical cross-section has tangentially extending therefrom at 78 a shallow inlet tube which is adapted to be secured to the bottom of a toilet seat 80 at the rear central portion thereof. The inlet tube 78 is open at its front end at a transversely elongated shallow intake or mouth 82. The tube 76 is preferably provided with reduced thickness tubular end portions 84, which are encircled and supported by brackets 86 carried by the toilet bowl 10 and upon which are journaled brackets 88 secured to the lid 14. Since the member 76 is rotatable in the brackets 86 and the brackets 88 are rotatable independently thereof, it will be seen that the tube 76 and brackets 86, 88 provide hinge means for both the toilet seat 12 and the lid 14.

Within one end portion of the tube 76 is mounted a suitable fan motor 90 having an elongated shaft 92 of a length to extend across the width of the shallow inlet member 78 and mounting fan blades 94. If desired the shaft may be journaled in a suitable apertured support 96 spaced inwardly from the right-hand end of the member 76, as viewed in FIG. 10. Within the end portion of the tube 76 outwardly of the fan 94 may be confined a suitable filter 98, such as activated charcoal, contained in a fabric or other container through which air may flow freely. A releasable bezel 100 may be mounted upon the end of the tube 76 to retain the charcoal filter. In the event the motor 90 is an alternating current motor, it can have connection to an electrical outlet by means of an electric cord (not shown) having a suitable switch therein (not shown). In the event that battery operation is desired, one or more batteries 102 may be mounted in the left hand end of the tube 76 and may have associated therewith positioning means or switching means 104 provided with an externally accessible actuator operable manually by the user to electrically energize the motor 90 or deenergize the same.

It will be understood that the batteries 102 need not be mounted within the tube 76 but, alternatively, can be mounted in a suitable socket or opening 106 in the seat

as illustrated in FIGS. 7 and 8, or may be mounted in a battery socket 108 formed in the lid 14, as illustrated in FIG. 9.

It will be understood that suitable switching means 5 will be provided with readily accessible actuating means for units in which the batteries are mounted in a seat socket 106 or a lid socket 108.

A slightly different construction or embodiment is illustrated in FIG. 11 wherein a filter 110 is mounted within the shallow inlet member 78 and the tube 76 is open at one end.

Another embodiment of the invention is illustrated in FIGS. 12 and 13, wherein a baffle member 112 extends across the inner end of the inlet member 78 to define a restricted outlet 114 for the shallow inlet member 78 and to define a restricted air flow passage 116 in the tube 76 centrally thereof. In this arrangement the motor 90 has a comparatively short shaft 92' mounting a fan blade 94 and serving to blow air through the restricted passage 116 past the restricted outlet 114 to induce a flow of air through the inlet member and thence through filter 98 mounted in the outlet end of the tube 76. It will be understood that the location of the filter in the tube 76 is optional and that in lieu thereof it may be mounted 20 within the inlet member 78, as shown at 110.

The embodiment of the invention illustrated in FIGS. 7 to 12 provides for a unitary deodorizing device in which all parts thereof, including the blower and the filter and inlet member or collecting means, are self-contained and 30 in which the power unit, such as the batteries, may also be self-contained. It will be understood that suitable retainer means, such as tube end cap 118, bezel 100 or means (not shown) to retain the filters 110 will be provided to accommodate access to and replacement of the 35 battery, the motor and the filter element.

While the preferred embodiments of the invention have been illustrated and described, it will be understood that changes in the construction may be made within the scope of the appended claims without departing from the 40 spirit of the invention.

We claim:

1. A deodorizing unit for a toilet device having a toilet bowl and a toilet seat, comprising an air intake member carried by said seat and a blower and filter unit 45 connected to said air intake member to deodorize air drawn thereby through said air intake member, said air intake member having a shallow wide tubular portion with close spaced substantially parallel top and bottom walls and side walls and located at the rear bottom portion of said toilet seat, said bottom wall having clearance with said toilet bowl, said shallow tubular portion having a horizontally elongated intake mouth spaced rearwardly from the adjacent inner edge of said seat, said air intake member including a substantially cylindrical tubular outlet portion communicating with said shallow tubular portion and positioned clear of the rear outer edge of said seat, said blower and filter unit including a motor driven fan and a filter, said motor driven fan being mounted in said cylindrical tubular portion and said filter 55 spanning a portion of said air intake member between the intake and outlet of the air flow path therethrough.

2. A deodorizing device as defined in claim 1, wherein said filter is housed in said cylindrical tubular portion.

3. A deodorizing device as defined in claim 1, where 65 in said filter is positioned in and spans said shallow tubular portion, and a partition is interposed between a portion of said shallow tubular portion and said cylindrical tubular portion to define merging air flow paths producing aspiration of air from said shallow portion and 70 discharge through said cylindrical tubular portion.

4. A deodorizing device as defined in claim 1, wherein said filter is housed in said air intake member, a partition at the junction of said shallow and cylindrical tubular portions defines merging air flow paths, said motor driven fan being mounted in said cylindrical tubular portion to 75

direct a flow of air therein past said partition to aspirate air from said shallow tubular portion.

5. A deodorizing device as defined in claim 1, wherein a battery is mounted in said air intake member to actuate said blower, and a control switch selectively actuates said 5 blower.
